MECHANISM FOR CLOTH FINISHING

Sanford L. Cluett, Troy, N. Y., assignor to Cluett, Peabody & Co., Inc., Troy, N. Y., a corporation of New York

Application August 15, 1932, Serial No. 628,851

5 Claims. (Cl. 26—58)

This invention relates to the shrinking of cloth by mechanical means and has for one of its principal objects to provide simpler and more compact mechanism for this purpose. Other objects of this invention and features of novelty and advantage will be apparent from this specification wherein the invention is explained by reference to a specific example thereof. In its preferred form as herein illustrated and described, the present invention makes use of mechanism generally known in the art as a "Palmer Stretcher", heretofore used near the end of a series of cloth finishing operations to extend the cloth to its original width preparatory to ironing. This "Palmer Stretcher" mechanism is herein diagrammatically illustrated in connection with the present invention which provides for the attainment of a satisfactory degree of lengthwise shrinkage.

20 In the drawing:

Fig. 1 is a diagrammatic side elevation of mechanism according to the present invention;

Fig. 2 is a diagrammatic plan view showing the stretching apparatus of Fig. 1; and

25 Fig. 3 is a diagrammatic side elevation on a larger scale, showing the effect upon the cloth of one of the web-edge engaging wheels and co-operating belts of the mechanism, and showing also the manner in which the edge of the cloth is held during widthwise stretching.

30 Referring to Fig. 1, cloth drying and ironing mechanism is diagrammatically shown as comprising a large heated rotary drum 11 of which the periphery is partially enveloped by an endless felt blanket 12, as well known in the art. The mechanism now to be described is adapted to perform the usual function of spreading or stretching the approaching fabric widthwise so that it will be of full width when dried and ironed.

35 However by this invention mechanism similar to that formerly used for such purpose is further enabled to shrink the fabric lengthwise by mechanical means, so as to deliver fabric to the ironing device in a state of lengthwise pre-shrinkage.

The mechanism preferably includes as indicated in Figs. 1 and 2, a pair of opposite circular plates 14 mounted on vertical hollow supports 15. These vertical supports are rotatably mounted for movement about vertical axes on any suitable platform or base 17. Conveniently, provision is made for rotating the two vertical supports 15 equally and in opposite directions, as by the provision of a rotatable shaft 18 having oppositely disposed threads at its two ends mesh-

ing with worm teeth on the vertical supports. The effect desired and attained is to provide for varying the angularity of the two plates 14 from parallel to an angle of divergence of several degrees as shown in Fig. 2.

5 Suitably mounted on the inner face of each of side plates 14 there is provided a wheel 19 having a rim 20 of several inches width. The rims of these wheels provide diverging arcuate paths for the edge portions of the fabric being treated. The machine may, if desired, include telescoping rods 19a pivotally fastened to each wheel 19 so as to connect the two wheels near their peripheries while permitting the wheels to turn in their somewhat divergent paths.

10 For confining the cloth to the divergent paths of the two wheel rims 20, the machine includes a pair of endless bands 23 which run on the rims 20 around more than half of their peripheries. As shown, each band 23 is guided in its return path 15 by two rollers 24, 25, mounted on a vertically adjustable bracket 26 carried by the corresponding side plate 14. Also after the band 23 leaves the periphery of the rim 20, it is guided by a roll 28 mounted on a bracket 30 carried by the plate 14. 20 A preferable feature of the invention constituting a significant change in machinery of this kind consists in the manner in which each endless band 23 approaches the surface of its corresponding rim 20. Referring to Fig. 1, a roller 32 is 25 so disposed that the band in reversing its curvature is nipped between the roller and the rim 20. The function and effect of this construction will be explained later in this specification. Each band 23 is tightened by adjustment of its upper supporting bracket, and thus by its tension presses against the rim 20, such pressure being augmented by small pressure rolls 47, 48 shown in Fig. 1.

30 Any suitable driving connections for the two wheels 19 may be employed, and may be of any known construction, preferably being partly contained within the two rotatable hollow supports 15 and permitting rotation of the same to adjust the angularity of the wheels 19 as is customary in machines of this type.

35 Fabric coming from any preceding cloth-finishing mechanism, such for example as a tentering machine 31, is suitably moistened in passing spray nozzles 33, 34 so as to contain for example from 5 to 15% of water, the fabric structure being thus rendered amenable to rearrangement by externally applied stresses. After passing around an idler roller 39, the fabric enters between the bands 23 and rims 20, both edges of the fabric 40

being firmly frictionally confined therebetween. In passing around the arcuate path defined by these rims 20, the fabric is stretched widthwise by the divergence of these members, the bands 5 23 diverging in the same degree as the rims 20. Upon leaving the rims 20, and passing around an idler roller 40, the fabric then runs onto the endless apron, blanket or belt 12 of the drying and ironing machine wherein the fabric is set in its 10 attained condition.

The device of my invention provides for a condition of lengthwise relaxation in the fabric passing about the arcuate path between the diverging bands 23 and cooperating wheel rims 20, such that 15 the fabric can respond to widthwise stretching by contraction in length substantially uniformly throughout the fabric. To this end, the web-edge holding arrangements of the device are preferably so shaped as to accommodate a certain 20 lengthwise slackness of fabric. This is best accomplished, as shown in Fig. 3 by providing each band 23 with serrations 41 adapted to receive slack edge portions of fabric between transverse ridges 42 as indicated in Fig. 3. It has been described above how the guide roller 32 and rims 25 20 nip the bands 23 as the latter reverse their curvature in running onto the rims 20. This feature is utilized to bring fabric into confinement between the bands and rims at a greater rate than 30 the bands travel during their divergence on the rims 20, thus to provide the desired lengthwise slack shown in Fig. 3. Each band 23 preferably includes a strong relatively non-extensible layer 23^a, which may for example be of strong non- 35 elastic fabric, and a relatively extensible layer 23^b which may for example be of rubber.

As the band 23 initially engages the fabric the ridges 42 on its fabric-engaging surface are relatively separated; and after the fabric is nipped 40 between the bands and the rims, these ridges approach each other sufficiently to cause the fabric which was initially extended lengthwise in its straight condition to be slack lengthwise in the arcuate path of the rims 20. Thus the rims are caused to receive fabric at a somewhat greater 45 rate than they travel.

The fabric, manipulated in this way, is free to shorten lengthwise during its widthwise stretching by the bands 23 and rims 20. Stress 50 imparted to the wefts by such stretching results in a straightening of the wefts; the fabric is internally plastic by virtue of its contained moisture, and the slack warps are free to crinkle and thus shorten the fabric as a whole. The serrated bands 23 enable such shortening to occur in the 55 edge portions of the web so that the web shortens uniformly in all portions. The subsequent ironing operation fixes the web in this shortened state.

It should be understood that the present disclosure is for the purpose of illustration only and 60 that this invention includes all modifications and equivalents which fall within the scope of the appended claims.

I claim:

1. Cloth finishing mechanism including rotatable elements providing arcuate paths of travel 65 for the edges of a web of cloth, traveling diver-

ing bands running in the arcuate paths defined by said rotatable elements and each shaped to hold the cloth against its respective rotatable element at longitudinally spaced points only, thereby providing free portions of cloth between such points, and means for bringing cloth into confinement between said bands and said rotatable elements at a faster rate than said bands travel during divergence, thereby to provide lengthwise slack to permit lengthwise shrinkage 10 during divergence of said web-confining bands. 5

2. Cloth finishing mechanism including rotatable elements providing arcuate paths of travel for the edges of a web of cloth, traveling bands running on said rotatable elements and adapted 15 to stretch the web of cloth in width during travel about said arcuate path, said bands having serrations adapted to receive slack portions of cloth, the shape of the bands being such that only the teeth of said serrations confine the cloth against 20 said rotatable elements, and means for so feeding cloth between said bands and said rotatable elements as to provide lengthwise slack portions between the teeth of said serrations on the bands. 25

3. Cloth finishing mechanism including traveling diverging flexible bands having serrations adapted to receive slack edge portions of cloth, in combination with members cooperating with said bands to grasp the edges of a cloth web 30 whereby divergence of said bands stretches the cloth widthwise, the bands and said cooperating members being shaped with relation to each other to grasp the cloth only at the teeth of the serrations, and means defining paths of travel for the bands such that the serrations on 35 each band approach each other to crowd cloth into said serrations preparatory to widthwise stretching. 40

4. Cloth finishing mechanism including opposed wheels adapted to turn at an angle to each other, endless bands running partially around said wheels and having on their sides which face the wheels a series of serrations adapted to receive slack cloth, the cooperating surfaces of said bands and wheels being shaped with relation to 45 each other to grasp the cloth only at the teeth of the serrations, and means for guiding said bands in endless paths away from and back to the peripheries of said wheels, including guide members about which the bands reverse their 50 curvature while pressing cloth against said wheels.

5. Cloth finishing mechanism including members defining arcuate paths for the edges of a web of cloth, traveling bands running on said 55 members and adapted to stretch the web of cloth in width during travel about said arcuate path, said bands having serrations adapted to receive slack portions of cloth, the shape of the bands being such that only the teeth of said serrations 60 confine the cloth against said members, and means for so feeding cloth between said bands and said members as to provide lengthwise slack portions between the teeth of said serrations on the bands. 65

SANFORD L. CLUETT.
